INVENTOR:

Charles A. Bailey.

BY

Arthur B. Jenkins.

ATTORNEY.

UNITED STATES PATENT OFFICE.

CHARLES A. BAILEY, OF CROMWELL, CONNECTICUT.

TOY PISTOL.

Application filed June 2, 1921. Serial No. 474,486.

To all whom it may concern:

Be it known that I, CHARLES A. BAILEY, a citizen of the United States, and a resident of Cromwell, in the county of Middlesex and 5 State of Connecticut, have invented new and Improved Toy Pistols, of which the following is a specification.

My invention relates to the class of toy pistols used for exploding paper caps, and 10 an object of my invention, among others, is to provide a pistol that shall be simple in construction and particularly effective in its operation.

One form of pistol embodying my invention and in the construction and use of 15 which the objects herein set out, as well as others, may be attained, is illustrated in the accompanying drawings, in which—

Figure 1 is a side view of a toy pistol embodying my invention.

Figure 2 is a top view of the same.

Figure 3 is a view in lengthwise vertical section through the same, and

Figure 4 is a view in cross section on a 25 plane denoted by dotted line 4—4 of Figure 3.

In the accompanying drawings the numeral 5 denotes the receiver of my improved toy pistol with a barrel 6 preferably formed 30 integral therewith and projecting from its front end. This structure is made from sheet metal bent into U-shape, the barrel 6 being subsequently bent into round or substantially round form in cross section. A 35 handle 7 is also formed from sheet metal bent into U-shape conforming substantially to the shape of the receiver 5, and the handle and receiver are of such width that the ends of their adjacent parts will be located one 40 within the other, in the structure herein shown (see Figure 1) the ends of the sides of the receiver being located within the upper end of the handle. The handle and receiver are rigidly secured together in any suitable 45 manner, as by spot welding.

A cover 8 is formed to close the opening between the side parts of the receiver at the front end underlying the barrel and also at the bottom for a substantial portion of its 50 length, this cover preferably having flanges 55 bent at an angle to the main part of the cover and to inclose the edges of the receiver, which edges are inserted within and between the flanges, the parts being firmly secured together in any suitable manner, as by spot welding. This cover has a tongue 10 bent

at an angle to its main part and of a width to extend upwardly between the side parts of the receiver, as shown in Figure 3, the upper end of this tongue being formed to 60 constitute an anvil 11 against which the paper caps may be exploded. In order to support such paper caps a rib 12 is formed in the tongue 10 at the bottom of the anvil, and sides 13 are formed integral with the 65 anvil and bent at an angle thereto for the purpose of retaining the paper caps in place. The handle and receiver are formed from a sheet metal blank of substantially uniform width.

A combined hammer and trigger is pivotally mounted between the side parts of the receiver, the hammer 14 projecting preferably out at the top of the receiver and the trigger 15 projecting out at the bottom of 75 the receiver and in front of the handle 7, as shown in Figure 3 of the drawings. The face of the hammer 14 is provided with projections 16 that serve to explode a paper cap in a manner to preserve the material intact, 80 thus preventing such cap from being blown to pieces and the pieces scattered at each explosion.

The trigger 15 is bent backwardly between the side parts of the handle 7, this backwardly extending part forming a spring support 17 that receives the end of a spring 18, one end of said spring being supported upon a ledge 19 at the lower back part of the handle and the opposite end of the 90 spring resting in a recess 20 in the underside of the spring support 17. The arrangement of the spring support and the spring is such that when the trigger is in its forward position and the hammer is consequently in 95 its rearward position, and as shown in Figure 3, the parts will be retained in such position by the spring. However, when the hammer is moved forward by pressure against the front face of the trigger, when the parts 100 reach a certain position, the spring will act to force the trigger backwardly and the hammer forwardly with a force sufficient to explode a cap on the anvil 11.

I claim—

1. A toy pistol comprising a handle with side parts arranged in substantially parallel relation, a receiver having side parts arranged in substantially parallel relation, the ends of the sides of the handle and receiver 110 extending one within the other between the sides thereof to provide contacting surface

sufficient for rigidly securing said parts together with the handle located at an angle to the receiver, and firing mechanism located within said structure.

3. A toy pistol comprising a handle bent to U-shape with the side parts arranged in substantially parallel relation, a receiver bent to U-shape and having side parts arranged in substantially parallel relation, the ends of the sides of the receiver and handle being located one within the other and between the sides thereof to provide contacting surfaces sufficient for rigidly securing said parts together, the closed edges of the receiver and handle being located at the outer edge of the structure whereby the handle is located at an angle to the receiver, means for securing the side parts of the receiver and handle together, and firing mechanism located within the structure.

3. A toy pistol comprising a receiver bent to U-shape with side parts arranged in substantially parallel relation, a barrel integrally formed with the receiver and projecting from one end thereof, a handle bent to U-shape with side parts located in substantially parallel relation, the end of the receiver being located within the upper end of the handle and between the sides thereof to provide contacting surfaces sufficient for rigidly securing said parts together, the closed edges of the handle and receiver being located at the top and back of the structure, means for securing the side parts of the receiver and handle together, and firing mechanism located within the structure.

4. A toy pistol comprising a receiver bent to U-shape, a cover closing the open edge of the receiver, a tongue integrally formed with the cover and projecting at an angle beyond the cover section and upwardly between the side parts of the receiver to form an anvil, and firing mechanism to cooperate with said anvil in firing operations.

5. A toy pistol comprising a receiver bent to U-shape, a cover closing the open edge of the receiver and having flanges within which the edges of the receiver are located, a tongue integrally formed with the cover and projecting at an angle thereto and beyond the cover section, upwardly between the side parts of the receiver to form an an-

vil, a rib formed in the tongue at the base of the anvil, and firing mechanism to cooperate with said anvil in the firing operation.

6. A toy pistol comprising a receiver bent to U-shape, a cover closing the open edge of the receiver and having flanges within which the edges of the receiver are located, a tongue projecting at an angle thereto and beyond the cover section, upwardly between the side parts of the receiver to form an anvil, sides integrally formed with the anvil at opposite edges thereof, and firing mechanism to cooperate with said anvil in the firing operation.

7. A toy pistol comprising a receiver and a handle, a hammer and a trigger formed from a single piece of metal and pivotally secured within the receiver, a spring support comprising an extension integrally formed with the trigger and projecting backwardly therefrom at an angle thereto and having a recess, and a spring secured within the handle and with one end resting within said recess.

8. A toy pistol comprising a receiver and a handle, a trigger and a hammer formed from a single piece of sheet metal pivotally secured within the receiver, said hammer and trigger comprising a backwardly extending extension from the lower end of the trigger located at an angle thereto, said extension having a recess, and a spring resting at one end upon a ledge in the lower end of the handle and with its opposite end located in said recess.

9. A toy pistol comprising a receiver and a handle, a hammer pivotally mounted in the receiver and having a face formed with a plurality of projections to prevent scattering of the pieces of paper cap or strip, an anvil to receive the impact of said projections, and means for operating the hammer.

10. A toy pistol comprising a receiver and a handle, a hammer and an anvil, one of which has a face formed with a plurality of projections to prevent scattering of the pieces of paper cap or strip, said hammer being pivotally mounted within the receiver.

CHARLES A. BAILEY.
